UNITED STATES PATENT OFFICE.

MADISON D. SHIPMAN, OF DE KALB, ILLINOIS.

GLOVE-FASTENING.

SPECIFICATION forming part of Letters Patent No. 447,369, dated March 3, 1891.

Application filed January 26, 1889. Serial No. 297,543. (No model.)

To all whom it may concern:

Be it known that I, MADISON D. SHIPMAN, a citizen of the United States, residing at De Kalb, in the county of De Kalb and State of Illinois, have invented certain new and useful Improvements in Studs of Separable Buttons, of which the following is a specification.

The object of my invention is the production of a light shell-form stud which has a bulbous-shaped head and a clinching eyelet portion integral with the head, and a base or upper-side washer which is securely fastened between said head and the clinching eyelet portion of the stud, which can be cheaply produced, conveniently handled or shipped without the liability of the two parts becoming separated, and which can be readily and securely attached to the fabric; and it consists in the peculiar construction, arrangement, and combination of parts hereinafter described, and then definitely claimed.

In the accompanying drawings, Figures 1, 2, and 3 are central vertical sections of buttons constructed according to my improvement; Fig. 4, a similar section of the head and stem part before being united with the washer; Fig. 5, a plan of a washer; Fig. 6, a vertical central section of the same; Fig. 7, a similar section of the washer and stem securely united ready to apply to the fabric; Fig. 8, a plan of an eyelet-clinching piece; Fig. 9, a central vertical section of the same; Fig. 10, a similar section of a washer to be employed with said clinching-piece; Fig. 11, a vertical section of a modified form of the stem.

Referring now to the details of the drawings by letter, A represents the stem or stud, having preferably a bulbous head a and a fastening-eyelet a' formed integral, and with a shoulder a^2 at the junction of the head and eyelet, as clearly shown in Fig. 4, which shoulder need not be large. In fact, it may simply be formed by the gradual increase of the neck to form the head. On this stem I secure a washer B (see Figs. 5 and 6) by pushing the eyelet or neck of the head through the same and then slightly spreading the eyelet or neck part by any appropriate tool, whereby a second shoulder a^3 is formed and the washer is securely fastened on the stem, as shown in Fig. 7. The stud thus formed, comprising the stem and washer securely fastened together

by a shoulder each side of the washer, prevents any accidental displacement of the washer, and is much superior to one in which the washer is not securely and permanently fastened to the stem. In fastening these studs to the cloth, leather, or other material on which they are employed the eyelet or neck a is first pushed through the cloth and then (preferably) a washer, such as E, is placed over the lower part of the eyelet, and the edge of the latter is then forced outward and clinched aound and over the edge of the hole in the washer, as shown in Fig. 1.

Another way of securing my stud to the fabric is shown in Fig. 2, in which a washer C, of the shape shown in section in Fig. 10, is secured within an eyelet-clinching piece D (see Figs. 2 and 8) by having its marginal flange d clinched all around the margin c of the washer C, and then entering the eyelet in the opening of the washer and forcing the central projection d' of the clinching-piece against the edge of said eyelet by any appropriate means, when the said edge will be turned outward between the washer and the clinching-piece, as shown in Fig. 2. If preferred, the stem may have an opening at the top, as shown in Fig. 11, or it may be slotted, as indicated in dotted lines in the same figure. I sometimes make the stem longer than is shown in Figs. 1 and 2, in which case I make an engaging-groove above the washer-holding shoulder, as shown in Fig. 3, to receive the button-catch of a coacting button-head. Thus different forms of studs may be used without departing from the main feature of my invention—to wit, the stem A having a washer securely fastened on its neck and adapted to have the lower part of said neck passed through the fabric and clinched. A stud comprising a stem and a washer securely fastened together, instead of being separate or insecurely fastened together, has various advantages, among which may be stated the following: First, the washer being securely fastened on the stem, only one article has to be picked up by the operator in attaching the stud to the fabric; second, the stud is always set perfectly upright in the fabric instead of being sidewise, as frequently occurs when setting studs with the loose washer; third, the accidental displacement of the washer from

off the stem when handling or shipping is prevented; fourth, a light weight shell-form head and attaching-eyelet integral, making a neat, compact, and secure attachment.

5 What I claim as new is—

1. As an article of manufacture, a stud A, composed of the head a, the clinching-tube a', the shoulders a² a³, and the perforated washer B, seated in the annular dépression between the shoulders a² and a³, the clinching-tube a' extending below said washer, substantially as and for the purpose set forth.
- 10

2. The combination of the hollow stem A, having an eyelet a', and a washer B, with a second washer C and a clinching-piece D, attached to said second washer and having a projection d' to clinch the eyelet, substantially as described.

15 MADISON D. SHIPMAN.
